CALIFORNIA.

RAILWAY-CROSSING SIGNAL.

Application filed April 11, 1925. Serial No. 22,332.

This invention relates to improvements in warning signal devices such as are installed on highways at grade crossings of railways, of a type actuated by approaching trains to give suitable warning to those on the highway.

As far as we are aware, all signals for this purpose now employed are either located at one side of the highway or are at a considerable height from the same. The result is that many drivers, especially at night, fail to see or take cognizance of the signal, and this failure is a frequent cause of accidents.

Sometimes a crossing warning or notice is painted in large letters on the highway itself, but this is not a warning signal in the true sense of the word, since there is nothing movable to indicate the approach of a train.

The principal object of our invention therefore is to provide a signal device mounted in the middle of the highway a certain distance on one side of the railway which, while normally out of sight below the road, will upon the approach of a train automatically rise from the ground and assume such a position that any driver, if he is paying any attention at all to his driving, cannot but help see the signal.

The signal is automatically illuminated when raised and is of such size as to be readily visible both by night and day. In addition we have arranged a siren or other audible signal to be sounded as long as the visible signal is raised.

Our signal is preferably actuated by a train in connection with the system shown in our co-pending application for patent on "railway-crossing signal actuating means", Serial No. 688,701, filed January 26th, 1924. With this system the signal ceases to be actuated as soon as the train actually reaches the crossing. The signal actuating circuits however as at present installed on railways may be used for actuating our signal if so desired.

The signal is not intended to act as a rigid barrier to bar the passage of traffic on the roads, but is to be located so that traffic can pass to either side of the same.

The signal automatically drops as soon as a train has passed, but in the event that a car driver should accidentally head his vehicle straight for the signal when the latter

is held raised by the closing of the actuating circuit, we have provided a safety trip actuated by such vehicle which will cause the signal to be quickly and temporarily dropped so that it will not be wrecked if the car is not stopped in time to avoid passing over the plane of the signal.

When the vehicle has passed the signal will be again automatically raised if the train is not yet out of the block in which the controlling circuits are located.

When the signal is lowered a car can run over the same without damage, although this should be avoided if possible, and would not be done by the average driver, since the signal apparatus as a whole is raised somewhat from the pavement and its presence can always be noted in time.

These objects we accomplish by means of such structure and relative arrangement of parts as will fully appear by a perusal of the following specification and claims.

In the drawings similar characters of reference indicate corresponding parts in the several views:

Fig. 1 is a sectional elevation of the signal apparatus showing the signal in its raised or operative position.

Fig. 2 is a similar view but with the signal lowered.

Fig. 3 is a cross section of the device taken through the fluid containing cylinder.

Referring now more particularly to the characters of reference on the drawings, the numeral 1 denotes a pair of signal members of suitable height and width, preferably about 1 x 2 feet. These members are of opaque material with letters 2 forming a suitable warning legend cut therethrough, translucent and preferably red panes 3 being placed behind the letters.

The signal members are of course disposed so as to face in opposed relation lengthwise of the highway 4 and preferably have a converging slope relative to each other toward their upper ends.

The members 1 are supported by a single piston rod or stem 5 having on its lower end a piston 6 slidable in a cylinder 7. This cylinder is mounted at the bottom of a pit 8 dug in the center of the roadway.

Rigid cover plates 9 extend from the opposite ends of the pit at the level of the rod with a slight upward slope toward the signal unit, terminating closely against the mem-

bers 1 adjacent the lower ends thereof when the latter are fully raised. Side plates 10 which support the plates 9 project up from the road level at the same slope as the plates, 5 the signal unit having a running fit therebetween.

The cylinder is of such a length that the stem 5 can move down from its upward limit a sufficient distance to cause the upper end or apex of the signal unit to lie in a horizontal plane about flush with the adjacent ends of the plates 9. A flap or hood 11 preferably of leather, rubber or the like is secured to the signal unit across the top thereof so as to overlap the ends of the plates 9 and adjacent portions of the plates 10 when the signal unit is lowered.

Thus the opening into the pit otherwise left open is covered and rain and dirt are 20 prevented from entering the pit.

Located in the pit is a tank 12 for a fluid, preferably oil. To pump the oil from the tank into the cylinder we provide a centrifugal pump 13 of ordinary character driven 25 by an electric motor 14, the current for which is supplied by a battery 15. The circuit wires 16 for the motor and battery lead from the pit to the railway, the circuit being closed by the passage of a train over that 30 section of track to which the wires are connected, as shown in the above mentioned co-pending application, or as is commonly done in connection with the actuation of present day signals.

35 The intake pipe 17 of the pump connects with the tank 12 at the bottom thereof and the discharge pipe 18 leads to the bottom of the cylinder 7. The bottom of the tank 12 is preferably lower than the bottom of the cylinder.

Since the motor will operate continuously as long as the train is on the length of track constituting the signal block, which is liable to be for different periods, whereas the raising of the signal consumes a fixed period of time, means must be provided to relieve the strain on the motor and other parts when the signal is raised to its full extent and the motor continues to operate.

50 This means comprises a port 19 in the cylinder just under the piston 6 when the latter is at the top of its stroke, a pipe 20 connected to said port leading back to the tank. The area of the port is such that sufficient pressure is retained in the cylinder to hold the signal raised as long as the pump is operating.

When the motor stops with the breaking of the track circuit the weight of the signal unit will cause the latter to displace the oil from the cylinder, said oil flowing back to the tank through the pump and thus allowing the signal to drop gradually and without jar.

60 65 65 To provide for a rapid drop of the signal

in the event that a vehicle should be moving directly toward and close to the signal we provide aprons 21 pivoted on base members 22 which are set flush with the highway a certain distance beyond and in longitudinal 70 alinement with the signal apparatus and on both sides of the same. These aprons extend to and overlap the cover plates 9 a certain distance in spaced relation thereto.

Leading from the cylinder at the bottom to the tank is a large outlet passage 23 in which is interposed a normally closed valve 24 of suitable character. This valve is held closed with a pressure greater than that of the oil in the cylinder at any time by spring 80 means 25 acting on an arm 26 connected to the axis of the valve.

Slidably mounted in the plates 9 are pins 27 bearing at their upper ends against the under faces of the aprons 21. The lower ends of the pins engage one end of levers 28 pivoted under the plates 9, the other ends of said levers being connected with the valve arm 26 by means of flexible members such as 90 wires 29.

These connecting mechanisms are so arranged that when the valve is closed the pins 27 are forced up to hold the aprons 21 clear of the plates 9. Also a depression of either apron, which causes the arm 26 to be turned to open the valve, does not impart 95 any movement to the other apron.

It will therefore be seen that if any wheel of a car runs onto either of the aprons the valve 26 will be instantly opened, causing the sudden release of oil from the cylinder and a consequent rapid drop of the signal unit.

The length of the aprons is preferably such that the signal will have time to drop before the wheels reach the plane of the signal units so that the latter will not be damaged by the passage of a wheel thereover.

Ordinarily, however the fact that the plates 9 and 10 and the entire apparatus present a normally raised appearance no matter if the signal is lowered, and the provision of mark or guide lines on the road both ways from the signal, as well as the central location of the apparatus in the road, will tend to prevent any driver from running 115 onto the apparatus.

The signal unit is illuminated by night and day by electric lights 30 placed in any suitable location behind the members 1 so as to shine through the letters 2, said lights 120 being lit whenever the motor circuit is closed.

An electric warning signal or siren 31 is also mounted in the pit, the circuit to the same being likewise closed upon the closing 125 of the motor circuit.

The hood 11 not only keeps the dirt and rain out of the pit but acts when the signal is raised to shade the latter, thus rendering the artificial illumination more effec- 130

tive in day time than would otherwise be the case.

It will be noted that all the oil pumped into the cylinder is returned to the tank, no matter which outlet from the cylinder may be utilized.

None of the oil is wasted therefore and a tank initially filled should last indefinitely if ordinary care in packing the moving parts is taken.

A pair of these signal devices actuated in common would be placed on the road for each crossing, one on each side of said crossing a certain distance therefrom.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention what we claim as new and useful and desire to secure by Letters Patent is:

1. A road signal device for railway crossings comprising a signal member normally depressed in the road, driven means for raising the signal above the road, means for causing the signal to normally remain raised as long as said means is being driven, and means actuated by a vehicle approaching on the road to within a predetermined distance of the signal, and in alinement therewith, for causing a sudden dropping of the signal to take place regardless of the operation of the driven means.

2. A road signal device for railway crossings comprising a signal member normally depressed in the road, a vertical cylinder below the signal, a piston therein, a stem between the piston and signal, a fluid-containing tank, and a pump to force oil from the tank to the cylinder below the piston therein, means for driving the pump, the signal normally remaining raised as long as the pump is in operation, and means actuated by a vehicle approaching on the road to within a predetermined distance of and in alinement with the signal for permitting a sudden flow of the fluid from the cylinder to take place regardless of the operation of the pump.

3. A road signal device for railway crossings comprising a signal member normally depressed in the road, a vertical cylinder below the signal, a piston therein, a stem between the piston and signal, means for

forcing a fluid into the cylinder to raise the piston and signal, the latter normally remaining raised as long as said means is in operation, an enlarged outlet from the cylinder near its bottom, a valve in said outlet, means for holding said valve normally closed, and means actuated by a vehicle approaching to within a certain distance of and in alinement with the signal for opening the valve whereby the fluid will rapidly escape and allow the signal to drop.

4. A road signal device for railway crossings comprising a signal member normally depressed in the road, a vertical cylinder below the signal, a piston therein, a stem between the piston and signal, means for forcing a fluid into the cylinder to raise the piston and signal, the latter normally remaining raised as long as said means is in operation, an enlarged outlet from the cylinder near its bottom, a valve in said outlet, means normally holding the valve closed against a predetermined pressure, an apron mounted in longitudinal alinement with the signal beyond the same, and adapted to receive a vehicle wheel thereon, the end of the apron adjacent the signal being normally held raised, and connecting means between the apron and valve whereby the latter is opened when a suitable pressure is placed on the apron.

5. A road signal device for railroad crossings comprising a signal member normally depressed in the road, fluid operated means for raising the signal, such means including a cylinder to contain a fluid and a piston therein operatively connected to the signal to cause the same to be raised when fluid is in the cylinder; means holding the signal raised as long as the raising means is in operation, a normally closed outlet from the cylinder, and means actuated by a vehicle approaching to within a certain distance of the signal for opening said outlet.

6. A road signal device for railway crossings comprising a signal member, driven means for operating the signal, means causing the signal to remain in operation as long as said means is being driven, means causing the signal to be inoperative when the operation of the driven means is discontinued, and additional means actuated by a vehicle approaching on the road to within a predetermined distance of the signal for causing the signal to be rendered inoperative regardless of the operation of the driven means.

In testimony whereof we affix our signatures.
